CYCLE SADDLE

Richard M. Timms, Memphis, Tenn., assignor to The
Troxel Manufacturing Company, Moscow, Tenn.

Filed Oct. 20, 1964, Ser. No. 82,241

Term of patent 14 years

(Cl. D90—16)

FIG. 1

FIG. 2

FIG. 5

FIG. 3

FIG. 4

FIG. 1 is a perspective view of a cycle saddle showing my new design.

FIG. 2 is a side elevational view thereof.

FIG. 3 is a top plan view thereof.

FIG. 4 is a view taken as on the line IV—IV of FIG. 2.

FIG. 5 is a front elevational view thereof.

I claim:

The ornamental design for a cycle saddle, as shown.
